[57] CLAIM

The ornamental design for a golf instructional mat or the like, as shown and described.

DESCRIPTION

FIG. 1 is a top plan view of the mat or the like showing my new design;

FIG. 2 is a side elevational view thereof, the opposite side being a mirror image thereof; and

FIG. 3 is a front elevational view thereof, the rear elevational view being a mirror image thereof.

FIG. 1

FIG. 2

FIG. 3
